(57) CLAIM

We claim the ornamental design for a human body detection sensor light operated on dry batteries, as shown and described.

DESCRIPTION

The application file contains at least one drawing executed in color. Copies of this patent application publication with color drawings will be provided by the Office upon request and payment of the necessary fee.

FIG. 1 is a front side view of a human body detection sensor light operated on dry batteries showing our new design;

FIG. 2 is a rear elevational view thereof;

FIG. 3 is a plan view thereof;

FIG. 4 is a bottom side view thereof;

FIG. 5 is a right view thereof; and,

FIG. 6 is a left view thereof.

We disclaim any surface ornamentation and written matter which form no part of the claimed design.
